ENGRAVING MACHINE

Ralph Scott Miller, New Barnet, England, assignor to Reginald Henry Windsor, London, England

Application August 8, 1945, Serial No. 609,603
In Great Britain August 28, 1944

5 Claims. (Cl. 33—23)

1

This invention provides an improved form of pattern holder for an engraving machine of the pantograph type, whereby a serial number can be combined with the other matter in the pattern holder, and changed after each engraving operation, thereby enabling the work pieces to be consecutively numbered.

The pattern holder according to the invention has a window in its bed and comprises one or more rotatably mounted copy drums disposed beneath the window, means for effecting step-by-step rotation of the drums to set up in the window copy representing consecutive serial numbers, and indexing means associated with the drums for ensuring that each digit pattern on each drum is fairly presented at the window.

Three forms of pattern holder according to the invention will now be described in detail, by way of example, with reference to the accompanying drawings, in which:

Fig. 1 is a perspective view of the first form, showing the pattern holder in position on the machine,

Fig. 2 is an enlarged plan view, partly in section, of the right hand end of the pattern holder,

Fig. 3 is a section, partly in elevation, on the line III—III in Fig. 2,

Fig. 4 is a section on the line IV—IV in Fig. 2,

Fig. 5 is a view similar to Fig. 4, showing a modified form of indexing device,

Fig. 6 is a plan view of an alternative arrangement of copy drums, and

Fig. 7 is a section on the line VII—VII in Fig. 6.

Like reference numerals indicate like parts throughout the figures.

Considering first of all Figs. 1—4, 10 represents the bed of the pattern holder, which is formed with a number of longitudinal V slides 40 for the reception of the patterns to be copied by the stylus 41 of the pantograph.

In the bed 10 is machined a window 11, beneath which are disposed, in a casing 12, six copy drums 13. These drums are rotatable on a common fixed shaft 14 and are of decagon form, bearing on their faces patterns corresponding to the numerals 0—9. The shaft 14 is formed with ten longitudinal grooves 15 (see Fig. 4), and each drum 13 carries a plunger 16, loaded by a spring 17, for engaging the grooves 15 and maintaining the drum with its selected digit pattern fairly presented at the window 11, so as to enable the digits to be accurately copied together with the other matter to be engraved.

Each drum 13 carries ten pins 18 projecting

2

from its right hand side face, these being received in circumferential grooves 19 in the adjoining drum, so that each drum is free to rotate on the shaft 14 independently of the others.

Associated with each drum is a press-button 20. The press-buttons are normally held projected in the positions illustrated by compression springs 21, but can be pressed inwards to rotate their associated drums through one step, i. e. to bring the next digit into position beneath the window. Pivoted at 22 to the inner end of each push-button 20 is a pawl 23, having a straight part, which normally rests (see Fig. 4) beneath the two lowermost pins 18 on the associated drum 13, and a tooth 25. A tension spring 26 holds the pawl in yielding engagement with the pins 18. The stroke of the pawl 23 is such that the drum 13 will be fed round through one step at each operation of the push button 20, the plunger 16 engaging in the next groove 15 in the shaft 14 to locate the drum in the new position.

An alternative form of indexing mechanism, to replace the grooves 15 and plungers 16, is shown in Fig. 5. This consists of a series of locking levers 56, one associated with each drum and all pivoted on a common rod 27. A spring 28 normally holds each lever 56 with its notch 29 engaging with one of the pins 18 on the associated drum.

In the arrangement shown in Figs. 6 and 7, a tens transfer mechanism is provided and step-by-step movement of the units drum, which is effected by movement of a lever 30, is sufficient to set up the consecutive serial numbers in the window. Two links 31, 32, the latter of which carries a handle 33, are pivoted to the casing 12 at points 34, 35 respectively. As later explained, clockwise pivotal movement of the link 32 from the position illustrated in Fig. 7 is effective to render the tens transfer mechanism inoperative.

The handle 30 is fixed to a shaft 38 on which is loosely mounted a wheel 43 coupled to the handle by a dog clutch 37. When the handle 30 is rotated clockwise as seen in Fig. 7, the wheel 43 is rotated with the handle. A stop, not shown, limits the rotary movement of the handle 30 to 36°, corresponding with one tenth of a revolution of the wheel 43.

The wheel 43 has ten notches 44, which cooperate with the pins 18 on the units drum 13, and move it one step at each operation of the handle 30. Fixed to the wheel 43 is an arm 46 carrying a pin 45. This enters a notch 47 in a wheel 48 rotatably mounted on a shaft 49 each time the

units drum steps on to present the digit 0 beneath the window, and turns the wheel 48 through one tenth of a revolution. Fixed to the wheel 48 is a wheel 50, the notches 51 of which engage the pins 18 of the tens drum, and turn this through one tenth of a revolution to effect the tens transfer. An arm 52 and pin 53 fixed to the wheel 50 operate, through the agency of wheels 54, 55 which are rotatable as a unit on the shaft 38 to transfer tens from the tens drum to the hundreds drum, and similar mechanism is provided between the drums representing higher denominations.

On return movement of the handle a spring 36 yields to allow the dog clutch 37 to slip, the pins 18 operating to hold the wheel 43 against reverse rotation.

By swinging the link 32 clockwise as seen in Fig. 7, the wheels on shafts 49, 38 are brought out of register with the pins 18 on the drums and the tens transfer mechanism is rendered inoperative.

If desired, instead of providing for manual operation of the lever 30, the latter can be arranged to be operated automatically, through a suitable trip gear, as each work piece is mounted in position on the work table (not shown).

If the drums 13 are of large diameter and the area covered by the digits on them is small, the drums can be round instead of polygonal, as illustrated.

What I claim as my invention and desire to secure by Letters Patent is:

1. In an engraving machine of the pantograph type, the combination with a flat bed for supporting a pattern to be copied and having thereon means for locating the pattern in relation to the bed and having therein a window in which copy representing a serial number can be displayed adjacent the pattern, of a numbering device located beneath the window and operable to set up in the window copy representing consecutive serial numbers, said numbering device comprising a plurality of denominational copy drums, resilient indexing means for locating the drums in adjusted position, and a member for imparting one step of movement to the units drum to display the next higher units digit in the window.

2. In an engraving machine of the pantograph type, the combination with a flat bed for supporting a pattern to be copied and having thereon slides for locating the pattern in relation to the bed and having therein a window in which copy representing a serial number can be displayed adjacent the pattern, of a numbering device located beneath the window and operable to set up in the window copy representing consecutive serial numbers, said numbering device comprising a plurality of denominational copy drums, resilient indexing means for locating the drums in adjusted position and a member for imparting one step of

movement to the units drum to display the next higher units digit in the window.

3. In an engraving machine of the pantograph type, the combination with a flat bed for supporting a pattern to be copied and having thereon means for locating the pattern in relation to the bed and having therein a window in which copy representing a serial number can be displayed adjacent the pattern, of a numbering device located beneath the window and operable to set up in the window copy representing consecutive serial numbers, said numbering device comprising a plurality of denominational copy drums, resilient indexing means for locating the drums in adjusted position, and a series of push buttons, one associated with each drum, each push button, when operated, causing one step of movement of its drum to display in the window the next higher digit on that drum.

4. Apparatus as claimed in claim 3, in which each button carries a pawl for coacting with the pins on the associated drum to rotate the same, the stroke of each pawl, when its push button is operated, being such as to rotate the associated drum through one step.

5. In an engraving machine of the pantograph type, the combination with a flat bed for supporting a pattern to be copied and having thereon means for locating the pattern in relation to the bed and having therein a window in which copy representing a serial number can be displayed adjacent the pattern, of a numbering device located beneath the window and operable to set up in the window copy representing consecutive serial numbers, said numbering device comprising a plurality of denominational copy drums, resilient indexing means for locating the drums in adjusted position, a pivoted lever, a notched wheel, a clutch coupling said lever to said notched wheel, pins on the units drum, said pins being operated by said notched wheel, on movement of said lever, to effect a single step of movement of said units drum, and a tens transfer mechanism for effecting carries over from each drum to the drum of next higher denomination.

RALPH SCOTT MILLER.
